Primary Examiner — Susan Moon Lee(74) *Attorney, Agent, or Firm* — Robert M. Downey, P.A.(57) **CLAIM**

The ornamental design for a pet water bowl and feed dish, as shown and described.

DESCRIPTION

FIG. 1 is a top, front perspective view of a pet water bowl and feed dish showing my new design;

FIG. 2 is a right side elevational view thereof, the left side elevational view being identical thereto;

FIG. 3 is a front elevational view thereof, the rear elevational view being identical thereto;

FIG. 4 is a top plan view thereof,

FIG. 5 is a bottom plan view thereof; and,

FIG. 6 is a bottom perspective view thereof.
